UNITED STATES PATENT OFFICE

JOSEPH S. BRYLKA, OF DU BOIS, PENNSYLVANIA

BOX LOCK

Application filed March 20, 1930. Serial No. 437,453.

This invention relates to certain new and useful improvements in box lock.

The primary object of the invention is to provide a lock embodying a hasp and a keeper and in which the keeper forms part of the lock mechanism for the box, the keeper for the hasp being displaceable by releasing part of the lock mechanism through the action of a key to expose another key receiving opening for the reception of the same key to release the main bolt of the lock and permit opening movement of the box cover.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a front elevational view, partly broken away and shown in section of a lock box constructed in accordance with the present invention;

Figure 2 is a top plan view, partly broken away to show the lock mechanism for the box cover;

Figure 3 is a vertical longitudinal sectional view taken on line 3—3 of Figure 2, showing one leg of a shackle that forms a keeper for the hasp on the box cover restrained from movement by a tensioned latch plate, and main locking bolt engaged with a keeper on the underside of the box cover;

Figure 4 is a vertical cross-sectional view taken on line 4—4 of Figure 3;

Figure 4A is a detail sectional view showing the box openings for the keeper shackle;

Figure 5 is a vertical longitudinal sectional view, similar to Figure 3, showing the tensioned latch plate for the leg of the shackle keeper disengaged therefrom;

Figure 6 is a vertical cross-sectional view, similar to Figure 4 showing the shackle keeper with its short legs removed from the box structure and turned to a position to expose a key receiving opening;

Figure 7 is a vertical longitudinal sectional view, similar to Figure 5 showing the main lock bolt shifted to released position

relative to the keeper carried by the box cover;

Figure 8 is a detail sectional view showing a part of the box structure and the lock mechanism in elevation;

Figure 9 is a detail sectional view taken on line 9—9 of Figure 3;

Figure 10 is a detail sectional view taken on line 10—10 of Figure 3 showing the tensioned latch plate engaged with the short leg 60 of the shackle keeper;

Figure 11 is a perspective view of the tensioned latch plate for the shackle keeper;

Figure 12 is a side elevational view of the 65 key employed for releasing the lock mechanism.

Referring more in detail to the accompanying drawings, there is illustrated a lock box having a front wall 1, a bottom wall, end walls, a rear wall and a cover 2 hinged to the rear wall as at 3 and carrying corner blocks 4 correctly to locate the cover on the box body when in closed position. The free edge of the hinged cover 2 carries a swinging hasp 5 received on a keeper 6 that is in the form of a U-shaped shackle associated with the front wall 1 of the box and with which a padlock 7 or other retaining means may be associated, the main lock for the box, however, being located interiorly thereof.

The lock mechanism within the box is mounted upon a plate 8 secured to the inner side of the front wall 1 of the box adjacent its upper edge, the plate having right angularly directed walls 10 and 11, the plate 11 intermediate its upper and lower edges carrying an angularly directed arm 12 parallel with the plate 8. The shackle keeper 6 comprises a long leg 13 and a short leg 14, the long leg 13 of the keeper shackle extending through registering openings in the front wall 1 of the box and the plate 8 and through an opening in the arm 12 while the short leg 14 of the keeper shackle extends through openings in the front wall of the plate and projects into a barrel 15 as shown in Figure 10 carried by the inner sides of the plate 8. A coil spring 16 surrounds the long leg of the keeper shackle between the plate 8 and

abutment 17 on said leg, for normally influencing the keeper shackle in a direction inwardly of the box.

The keeper shackle is normally locked within the box by means of a tensioned latch 18 slidably mounted between guides 19 on the plate 8, a finger 20 of the latch 18 being engaged in a side notch 21 formed in the short leg 14 of the keeper shackle. One end 10 of the latch 18 carries an angle flange 22 having an opening 23 therein to receive one end of a coil spring 24, the other end of the coil spring being attached to the angle wall 10 on the plate 8 for normally influencing the latch 18 in a direction toward the short leg of the keeper shackle. The end of the latch 18 opposite the angle end 22 is provided with a lateral flange 25 having upstanding abutments 26.

20 The key for operating the lock mechanism is shown in Figure 12 and comprising a shank 27 having an angle ward 28 at one end, a collar 29 intermediate its ends to limit projecting movement of the key into the lock and 25 a handle 30 upon its other end. To release the finger 20 of the latch 18 from the notch in the side of the short leg of the keeper shackle, the key 27 is inserted through the opening 31 in the front wall of the box to be 30 positioned between the abutment 26, it being understood that the side of the barrel 15 is slotted as at 15a to accommodate the passage thereinto of the finger 20 for engagement with the shackle leg. The key 27 is then 35 turned to engage the abutment 26 adjacent the latch 18 and to shift the latch against the tension of the spring 24 and at which time, a pull upon the latch keeper 6 will move the short leg 14 thereof outwardly of the box 40 and expose a key receiving opening 32. Return sliding movement of the latch 18 under influence of the spring 24 is limited by the end abutment 26 engaging the angle end wall 11 of the plate 8 for also limiting projecting 45 movement of the latch finger 20 into the barrel 15.

The locking bolt for the hinged cover 2 is in the form of a U-shaped rod comprising a bolt 33 and a guide rod 34 connected at adjacent ends by the cross rod 35, the bolt 33 and rod 34 being slidable through openings in the angle walls 10 and 11 of the plate 8 with the cross rod 35 positioned outwardly of the wall 10. The end of the bolt 33 projecting 55 through the end wall 11 is adapted for engagement with a keeper 36 depending from the hinged cover 2. The bolt frame is normally tensioned in a direction of movement 60 for latching engagement with the keeper 36 by the coil spring 37 having one end extended through the end wall 10 of the plate 8 and engaged with the cross rod 35 of the bolt frame as shown at 38, while the other end of 65 the spring 37 is engaged with the finger 39

projecting outwardly from the plate 8 as shown in several of the figures.

With the latch finger 20 disengaged from the side notch in the short leg 14 of the keeper shackle 6 and said short leg removed from the box and displaced laterally of the key receiving opening 32, the key shown in Figure 12 is then inserted in the opening 32 for passage through the barrel 15, the side of the barrel being slotted as at 40 to accommodate the passage of the key ward 28 as shown in Figure 7. The ward 28 of the key is then located in engagement with the lug 41 projecting laterally from the guide rod 34 and upon rotation of the key 27, the guide rod, together with the bolt 33 are shifted against the tension of the spring 37 to disengage the bolt 33 from the keeper 36 as shown in Figure 7 and at which time the cover 2 of the box may be opened upon its hinged 55 mounting. Movement of the bolt frame against the tension of the spring 37 is controlled by the stop 42 upon the end of the guide rod 34 that moves into engagement with the end wall of the plate 8.

From the above detailed description of the invention, it is believed that the construction and operation thereof will at once be apparent, it being noted that the padlock 7 engaged with the keeper shackle 6 as shown in Figure 1 is foreign to the particular lock mechanism forming the basis of this application, except that the hasp 5 overlies the key receiving opening 31 which permits operation of the sliding latch 18. It is necessary to release the sliding latch from engagement with the short leg of the keeper shackle in order to permit the short leg to be removed from the key receiving opening 32 and through which opening the key for operating the bolt 33 is passed, and while there is herein shown and described the preferred embodiment of the invention, it is nevertheless to be understood that minor changes may be made therein without departing from the 105 spirit and scope of the invention as claimed.

I claim:—

1. In a lock box having a box body and hinged cover, lock mechanism for the cover comprising a key operated sliding bolt on the body and a keeper on the cover, a hasp on the cover and a restraining keeper shackle on the body, and said keeper shackle for said hasp being shiftable to expose a key opening 110 for access to the sliding bolt.

2. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, and said box having an opening adapted to be covered by 125

the hasp for controlling access to the restraining devices for the keeper shackle.

3. In a lock box having a box body and hinged cover, a lock mechanism for the cover comprising a sliding bolt on the body and a keeper on the cover, a hasp on the cover and a restraining keeper shackle on the body, said keeper shackle being shiftable to expose a key opening for access to the sliding bolt, the keeper shackle including a tensioned long leg slidable in the body, a normally restrained short leg removable from the body to expose the key opening, restraining means for the short leg of the keeper shackle including a sliding tensioned latch engaged with a side of the short leg, and said latch being disengaged from the short leg of the keeper shackle by a key insertible through the opening exposed by the hasp.

15 4. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the keeper shackle including a tensioned long leg slidable in the body, and a normally restrained short leg removable from the body to expose the key opening.

30 5. In a lock box having a box body and hinged cover, a lock mechanism for the cover comprising a sliding bolt on the body and a keeper on the cover, a hasp on the cover and a restrained keeper shackle on the body, said keeper shackle being shiftable to expose a key opening for access to the sliding bolt, the keeper shackle including a tensioned long leg slidable in the body, a short leg removable from the body to expose the key opening, and restraining means for the short leg of the keeper shackle including a sliding tensioned latch engaged with a side of the short leg.

45 6. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the keeper shackle including a tensioned long leg slidable in the body, a short leg removable from the body to expose the key opening, and restraining means for the short leg of the keeper shackle including a sliding tensioned latch engaged with a side of the short leg.

55 7. In a lock box having a box body and hinged cover, a lock mechanism for the cover comprising a sliding bolt on the body and a keeper on the cover, a hasp on the cover and a

restrained keeper shackle on the body, said keeper shackle being shiftable to expose a key opening for access to the sliding bolt, the keeper shackle including a tensioned long leg slidable in the body, a normally restrained short leg removable from the body to expose the key opening, restraining means for the short leg of the keeper shackle including a sliding tensioned latch engaged with a side of the short leg, and said latch being disengaged from the short leg of the keeper shackle by a key insertible through the opening exposed by the hasp.

8. In a lock box having a box body and hinged cover, a lock mechanism for the cover comprising a sliding bolt on the body a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the keeper shackle including a tensioned long leg slidable in the body, a short leg removable from the body to expose the key opening, restraining means for the short leg of the keeper shackle including a sliding tensioned latch engaged with a side of the short leg, and said latch being disengaged from the short leg of the keeper shackle by a key insertible through the opening exposed by the hasp.

9. In a lock box having a box body and hinged cover, a lock mechanism for the cover comprising a sliding bolt on the body and a keeper on the cover, a hasp on the cover and a restrained keeper shackle on the body, said keeper shackle being shiftable to expose a key opening for excess to the sliding bolt, the sliding bolt being spring pressed into engagement with the keeper on the cover, a guide rod carried by the bolt, and said guide rod and bolt adapted to be operated by a key insertible in the key opening exposed by the short leg of the shackle.

10. In a lock box having a box body and hinge cover, a lock mechanism for the cover comprising a sliding bolt on the body and a keeper on the cover, a hasp on the cover and a keeper shackle on the body, restraining devices for the keeper shackle said keeper shackle being shiftable to expose a key opening for access to the sliding bolt, said box having an opening adapted to be covered by the hasp for controlling access to the restraining devices for the keeper shackle, the sliding bolt being spring pressed into engagement with the keeper on the cover, a guide rod carried by the bolt, and said guide rod and bolt adapted to be operated by a key insertible in the key opening exposed by the short leg of the shackle.

11. In a lock box having a box body and hinged cover, a lock mechanism for the cover

comprising a sliding bolt on the body and a keeper on the cover, a hasp on the cover and a restrained keeper shackle on the body, said keeper shackle being shiftable to expose a key opening for access to the sliding bolt, the sliding bolt being spring pressed into engagement with the keeper on the cover, a guide rod carried by the bolt, said guide rod and bolt adapted to be operated by a key insertible in the key opening exposed by the short leg of the shackle, a barrel on the body aligned with the key opening, and having a side slot for the passage of a lateral ward on the key.

12. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the sliding bolt being spring pressed into engagement with the keeper on the cover, a guide rod carried by the bolt, said guide rod and bolt adapted to be operated by a key insertible in the key opening exposed by the short leg of the shackle, a barrel on the body aligned with the key opening, and having a side slot for the passage of a lateral ward on the key.

13. In a lock box having a box body and hinged cover, a lock mechanism for the cover comprising a sliding bolt on the body and a keeper on the cover, a hasp on the cover and a restrained keeper shackle on the body, said keeper shackle being shiftable to expose a key opening for access to the sliding bolt, the keeper shackle including a tensioned long leg slidable in the body, a short leg removable from the body to expose the key opening, and means for normally restraining the short leg from movement the sliding bolt being spring pressed into engagement with the keeper on the cover, a guide rod carried by the bolt, and said guide rod and bolt adapted to be operated by a key insertible in the key opening exposed by the short leg of the shackle.

14. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the keeper shackle including a tensioned long leg slidable in the body, a short leg removable from the body to expose the key opening, and means for normally restraining the short leg from the movement the sliding bolt being

spring pressed into engagement with the keeper on the cover, a guide rod carried by the bolt, and said guide rod and bolt adapted to be operated by a key insertible in the key opening exposed by the short leg of the shackle.

15. In a lock box having a box body and hinged cover, a lock mechanism for the cover comprising a sliding bolt on the body and a keeper on the cover, a hasp on the cover and a restrained keeper shackle on the body, said keeper shackle being shiftable to expose a key opening for access to the sliding bolt, the keeper shackle including a tensioned long leg slidable in the body, a normally restrained short leg removable from the body to expose the key opening, restraining means for the short leg of the keeper shackle including a sliding tensioned latch engaged with a side of the short leg, a barrel on the body aligned with the key opening, and having a side slot for the passage of a lateral ward on the key.

16. In a lock box having a box body and hinged cover, a lock mechanism for the cover comprising a sliding bolt on the body and a keeper on the cover, a hasp on the cover and a keeper shackle on the body, restraining devices for the keeper shackle, said keeper shackle being shiftable to expose a key opening for access to the sliding bolt, said box having an opening adapted to be covered by the hasp for controlling access to the restraining devices for the keeper shackle, the keeper shackle including a tensioned long leg slidable in the body, a short leg removable from the body to expose the key opening, restraining means for the short leg of the keeper shackle including a sliding tensioned latch engaged with a side of the short leg, a barrel on the body aligned with the key opening, and having a side slot for the passage of a lateral ward on the key.

In testimony whereof I affix my signature.
JOSEPH S. BRYLKKA.
